UNITED STATES PATENT OFFICE

SVEN SVENSON, OF FOND DU LAC, WISCONSIN

STARTING AND STOPPING DEVICE FOR AIRPLANES

Application filed May 7, 1928. Serial No. 275,845.

My invention relates to airplanes.

It resides, first in a means for effecting the take-off of the plane from its landing place, such means comprising a winding drum 5 which can be operated at a high speed, and in its rotation be caused to draw upon and reel a cable, the free end of the latter being detachably connected at a point fixed with relation to the field, so that an initial movement of great velocity is imparted to the plane.

The connection of the free end of the cable with its fixed point of anchorage, is detached in the concluding stage of the initial movement of the plane, and an enlargement upon the end of the now disconnected cable is caused to actuate devices which will disconnect the drum from its operating means and interrupt its further movement of rotation.

20 The invention resides, second, in the provision of electro-magnetic means for arresting the travel of the plane, when the latter reaches its landing place. Such means comprises a metal plate fixed at the place of landing. The plane is provided with a co-operating magnet which is energized as the landing is made, by a suitable generator carried by the plane, so that as the plane alights upon the metal plate, the magnetic force becomes effective and acts with great power to retard and then terminate the further movement of the plane, and quickly brings it to a state of rest, in which position it will remain until the current to the magnet is broken.

Having thus outlined the nature and purposes of my invention, I will now describe the embodiment shown, and point out the novelty thereof in the appended claims.

40 In the accompanying drawing:

Figure 1 is a view showing in side elevation a conventional airplane at rest upon a metallic landing field, in accordance with my invention;

Fig. 2 is an enlarged view, similar to Fig. 1, with part of the body of the plane broken out, to show features of the mechanism;

Fig. 3 is an enlarged transverse sectional view, on the line 3-3, Fig. 2, showing de-

tails of the magnet, the generator, and the controlling switch.

Fig. 4 is a fragmentary plan view showing a portion of the metallic field and the means by which the detachable connection of the 55 free end of the cable with the fixed anchorage is effected.

In the drawing, the numeral 10 indicates the body of an airplane of, it may be, conventional construction.

Connected to and driven from the motor shaft, is a suitable journaled counter shaft 11, having a winding drum 12, mounted for free rotation thereon. A sliding clutch member 13, splined upon the shaft 11, is adapted to 65 be engaged with the drum 12, and couple the latter to the shaft 11, so as to be rotated therewith. A clutch-actuating lever 14 is pivoted upon a bracket 15. Extending rearwardly, and in position to be operated by the 70 pilot of the plane, is a hand lever 16, connected to the clutch-actuating lever 14, in the line of the pivotal point of the latter. By this means, the drum 12 may be clutched to the shaft 11, and unclutched therefrom. 75

Extending forwardly of the pivot of the clutch-actuating lever 14, and connected thereto, is a radial arm 17, to the free end of which is connected the upper end of a link 18, the lower end of which is provided with a 80 constricted angular eye piece 19, for a purpose which will later be described.

A cable 20 of considerable length is attached at one end to the drum 12, and normally wound thereon, the said cable passing 85 through the eye piece 19 of the link 18, and having upon its farther free end, a button or knot, or other enlargement, 21, of a diameter exceeding that of the eye 19, the constriction of which forbids the passage of the said enlargement therethrough.

With the airplane at rest, the cable is unwound from the reel, and extended to the far edge of the field. At this place, a post 22, with a notch or upwardly opening fork is 95 firmly fixed. The end of the cable is laid in the notch with the enlargement of the cable resting against the outer side of the post.

When the motor of the airplane is started, the clutch member 13 is thrown into engage- 100

ment with the drum 12, by lifting the hand lever 16, and the plane moves forward with the winding up of the cable. As the speed of the motor is increased, the speed of the airplane is accelerated. The plane will rise, and the enlargement 21 at the free end of the cable will be removed from the notch or upwardly opening fork of the post 22. Thereafter, the said enlargement of the cable will reach the constricted eye piece 19 of the link 18, and, through the instrumentality of said link, will cause the radial arm 17 to be lifted, the clutch-actuating lever 14 to be raised, and the sliding clutch member 13 to be withdrawn from engagement with the winding drum 12, to thus free the said drum from rotating connection with the counter shaft 11. Thereupon, the winding drum will assume a stationary position, as will be obvious, and the airplane will proceed without interruption.

To effect the stopping of the airplane and check its movement upon landing, I form a landing area by arranging a flat metal surface or sheet 23, secured in immovable position, at the place where the desired landing is to be made. Upon the airplane, and preferably at its under side near the rear end, I arrange a magnet 24, the poles 25 and 26 of which project downwardly to the ground line of the machine. The poles are arranged at the opposite ends of the core 27, which latter may have a slight rotatory motion in the coil 28, so as to adapt the shoe faces of the poles of the magnet 24, to inequalities of the landing sheet, and permit a perfect contact to be made. A stay wire 29, attached forwardly to the body of the airplane, and rearwardly to the poles of the magnet, serves to limit the rotating motion of the poles, and hold them in a substantially horizontal plane.

To energize the magnet 24, I equip the airplane with a generator 30 of suitable capacity, a battery being illustrated as a generator. Connections 31 and 32 lead from the generator to the magnet. In the circuit 32, I insert a controlling switch 33, and a rheostat 34, by means of which the power of the magnet may be regulated by the pilot.

As the plane approaches the landing sheet, the switch is thrown on, and the magnet energized by the current passing from the generator. The magnet thus attracts the fixed metal sheet 23, and the power thereof exerts a pressure which acts as a drag upon the airplane, and retards its further movement. The magnetic attraction may be increased through the rheostat, until the plane is brought to a state of rest. Reversal of the switch will break the connection, and leave the plane free for another flight.

It is desirable, in some instances, that the metal plate 23, be arranged at an angle from the horizontal, so as to present an added resistance to the movement of the plane, up-

wardly of the inclined surface of the landing plate.

Having thus described my invention, what I claim and desire to secure by Letters Patent of the United States, is:

1. An airplane provided with a magnet at its ground line, the said magnet comprising two poles and a coil for energizing the magnet, the poles being journaled so as to have a rotative movement with relation to the coil, a generator for supplying current to the coil, and means controlled by the pilot of the plane for energizing the coil to cause the magnet to function as a stop for the plane when landing.

2. An airplane provided with a magnet at its ground line, the said magnet comprising a coil and poles having a rotative movement with relation thereto, and means for energizing the magnet to cause it to function as a stop for the plane when landing.

In testimony whereof, I have signed my name at Milwaukee, this 21st day of April, 1928.

SVEN SVENSON.
